(57) **CLAIM**

The ornamental design for a LED candle, as shown and described.

DESCRIPTION

FIG. 1 is an isometric view of a first embodiment of a LED candle showing may new design;

FIG. 2 is a front elevation view of the first embodiment thereof;

FIG. 3 is a rear elevation view of the first embodiment thereof;

FIG. 4 is a left elevation view of the first embodiment thereof;

FIG. 5 is a right elevation view of the first embodiment thereof;

FIG. 6 is a top plan view of the first embodiment thereof;

FIG. 7 is a bottom plan view of the first embodiment thereof;

FIG. 8 is an isometric view of a second embodiment of the LED candle;

FIG. 9 is a front elevation view of the second embodiment thereof;

FIG. 10 is a rear elevation view of the second embodiment thereof;

FIG. 11 is a left elevation view of the second embodiment thereof;

FIG. 12 is a right elevation view of the second embodiment thereof;

FIG. 13 is a top plan view of the second embodiment thereof; and,

FIG. 14 is a bottom plan view of the second embodiment thereof.

The broken lines shown in the drawings illustrate portions of the LED candle that form no part of the claimed design.
